UNITED STATES PATENT OFFICE

LESLIE A. HOLMAN, OF WALTHAM, MASSACHUSETTS

HEEL PRESS

Application filed May 6, 1926. Serial No. 107,157.

This invention relates to heel press adapted to be used in connection with heel making machines for automatically receiving assembled heels from the heel making machine, subjecting the same to pressure and for delivering the pressed heels and although designed with particular reference to the heel making machine shown in an application filed by me in the United States Patent Office, October 29, 1921, Serial No. 496,201, yet it is capable of use in connection with any heel building machine.

In the making of heels by machine, the lifts in each heel are generally held together by glue or other adhesive and it is the common practice to subject the heels to a preliminary pressure after they emerge from the machine and while the adhesive is setting to get a firm, compact bond between the various lifts of the heel, after which they are later subjected to heavy hydraulic pressure to solidify and compact the heel into a more or less homogeneous structure. The preliminary pressure has most generally been applied by hand presses or similar devices, the heels being arranged on a board which is placed in the press, but this operation is not as a rule satisfactory because the heels vary in thickness so that the thicker heels on the board sustain most of the pressure and the thinner heels are pressed only to a slight extent and in some cases not at all.

In subjecting wedge-shaped heels to this preliminary pressure, the difficulties are further enhanced because a wedge-shaped blank must be mounted on top of each heel in order that the pressure may be directed evenly. In addition to the ineffectiveness of the pressure applied in this operation, the necessary handling of the lifts, the provision of suitable end pieces or other devices and the time consumed involves an appreciable expense which increases materially the cost of production of the heels.

The main object of my invention is the provision of a heel press adapted for receiving and holding heels under pressure for a sufficient length of time to permit the adhesive holding the lifts together in heel form to

set and harden and for discharging the heels at the conclusion of the pressing operation.

Another object of my invention is the provision of a heel press which is adapted for use in connection with any suitable form of heel making machine and is adapted for being mounted in connection with such machine so that the heels may be transferred as soon as completed from the heel making machine to the heel press.

An additional object of the invention is the provision of a heel press which is adapted for pressing wedge-shaped heels as well as flat heels.

Another object of the invention is the provision of a press which is entirely automatic in its action and which after started in operation does not require any appreciable amount of attention.

Other objects of the invention will be more specifically set forth and pointed out herein-after.

In its preferred embodiment, my invention contemplates a heel press comprising a plurality of pressing units mounted on a frame which is adapted for movement to present the units in a continuous sequence to a feeding station where the heels to be pressed are fed into the units. Each unit is adapted to hold a column of heels under a constant pressure preferably secured by restricting the outlet opening in the unit and providing locking means at the inlet end for holding the heels within the unit. The heels are forced into the inlet end of the unit and whenever a heel is forced in another heel is forced out at the outlet end of the unit, so that a heel travels from the inlet end to the outlet end under a constant pressure. The pressing unit may be made in any form suitable for holding a column of heels and the means for restricting its outlet end may be of various forms adapted to offer a resistance to the passage of heels sufficient to maintain the entire column in the unit under a constant pressure.

The frame may also be of any suitable form for carrying one or more units but preferably is circular with a plurality of units in circular arrangement to permit them to be advanced to the feeding station in se-

55

quence by an intermittent rotation of the frame. The heels are forced through locking devices into the units flatwise by a plunger mechanism which forces the entire column of heels forward through the pressing unit to permit the heel being fed to pass the locking devices and to be held within the unit thereby and the forward movement of the column forces a heel out through the restricted end.

When the heel-press is used in conjunction with a heel making machine, it is located at the delivery end of the latter and means are provided for transferring heels from the said end of the heel making machine to the feeding station of the press. The machine is designed for automatic operation entirely, the product of the heel making machine being fed into the press as fast as delivered and after the heels are pressed until the adhesive has thoroughly set and dried, they are delivered into a suitable receptacle.

My invention further contemplates the provision of means whereby wedge-shaped heels may be handled by the machine automatically and with the same facility as flat heels. A suitable magazine is provided at the feeding station for carrying a supply of wedge-shaped blocks for insertion between the breasts of adjacent heels to permit the formation of regular columns of heels and a block is fed into the unit with the heel. At the outlet end of each unit are means for separating the blocks from the heels by directing the heels in one direction for travel through a chute into a receptacle and the wedge blocks in another direction to return to the wedge block magazine. The blocks are thus used over and over and each time that a block and a heel are forced into the inlet end of a unit a block and a heel pass out at the outlet end of the unit.

When the heel press is started in operation with the units empty it is necessary to load each unit in turn to full capacity in order to develop a pressure as soon as possible. The pressure is not attained in a unit until the column of heels has been built up sufficiently to feel the effect of the restricted outlet. For this reason, the mechanism for rotating the frame in a step-by-step manner is adapted to be rendered inoperative to permit the frame to remain stationary at the feeding station until the unit has been filled. After one unit is filled, the frame is rotated one step to fill the next unit and so on until all the units are filled after which the machine is designed to be operated in the usual manner, the frame being rotated one step after each feeding operation in order to present the units in sequence to the feeding station.

In the drawings illustrating one form of my invention, Figure 1 is a front elevation of a heel press constructed and adapted for operation in accordance with my invention and shown located at the delivery end of a

heel building machine with the conveying member of said heel building machine arranged for delivering completed heel piles to said press; Fig. 2 is a plan view of the driving mechanism for the heel press and 70 the conveyor element of the heel building machine, a portion of the top plate of the frame being broken away to disclose the driving mechanism thereunder; Fig. 3 is a detail plan view on an enlarged scale of the indexing mechanism for rotating the heel press frame; Fig. 4 is an elevation partly in section of the index pawl looking from left to right in Fig. 3; Fig. 5 is a partial cross-sectional view of the pressing units and frame 80 on line 5-5 in Fig. 1 looking downward and on an enlarged scale; Fig. 6 is a partial cross-sectional view on line 6-6 in Fig. 1 also on an enlarged scale showing the frictional means arranged at the top of the units 85 for opposing the ejection of heel lifts from the pressing unit to develop pressure therein; Fig. 7 is a view in perspective of one form of frictional means; Fig. 8 is a side elevation of the mechanism for moving lifts from the 90 conveyor to a station for delivery into the pressing units; Fig. 9 is a side elevation of a plunger mechanism for moving heels from said station into the pressing units of the press; Figs. 8 and 9 being taken from the 95 same point of view; Fig. 10 is a side elevation of the indexing mechanism and keeper-pawl; Fig. 11 is a diagrammatic assembly 100 view of the five operating cams mounted on the main shaft and their engaging elements 105 all shown in timed position; Fig. 12 is a side elevation of the means for operating the wedge-gate to permit rotation of the pressing unit frame; Fig. 13 is a front elevation of the lower portion of a pressing unit and 110 mechanism for centering heels after they are moved from the conveyor to the station underneath the pressing unit; Fig. 14 is a side elevation of the lower portion of a wedge 115 slide and the mechanism for moving heels from the conveyor to the station with centering and injecting mechanism; Fig. 15 is a plan view of the centering wings; Fig. 16 is a front elevation of a pressing unit; Fig. 17 is a vertical longitudinal central cross-sectional view of a pressing unit on line 17-17 in Fig. 16; Fig. 18 is a vertical longitudinal sectional view on line 18-18 of Fig. 13; showing the switch for inserting wedge plates between heels in inoperative position; Fig. 19 is a similar view to Fig. 18 but showing the switch in position to permit a wedge plate to drop by gravity on top of an incoming heel, both of these figures being designed to indicate the initial loading position. Fig. 120 19 shows the operation of the switch when the unit is being loaded for the first time; Fig. 20 is a side elevation of the wedge-gate in open position; Fig. 21 is a front elevation of the wedge-plate storage rack; and Fig. 22 125 130

is a perspective view of the wedge plate for use in connection with wedge-shaped heels.

The frame of the machine

The frame of the machine may be of any suitable form but as shown comprises a table-like structure for carrying the operating instrumentalities for transferring heels from the heel making machine to the pressing units and a frame arranged on one side of and above said table for carrying a plurality of pressing units. The table-like structure comprises a square frame 30 supported by four legs 31 joined together at their bottom ends by braces 32 (Fig. 1). A base-plate 33 is mounted on top the frame 30 over which runs the conveyor of the heel making machine for delivering assembled heels to the press and below the base-plate is mounted a sub-base plate 35 for carrying the driving and operating mechanisms, the plate 35 being attached to the brace 32 by suitable braces 36.

On the rear side of the table frame is the press-frame comprising a vertical shaft 37 carrying two circular disks 39 having hub portions 40 fitting and attached to said shaft (Fig. 5). The latter is rotatably supported in upright position by a triangular bracket 42 fastened by bolts 43 to the base-plate 33 and by a rear extension 44 of the sub-base plate 35 (Fig. 8). To facilitate the rotation of the shaft 37, its lower end may be provided with ball bearings, one member 45 of the bearing being fixed to the shaft and the other member 46 in the extension 44. The two disks 39 are spaced apart on the shaft and are of a thickness sufficient to support without warping the weight of the pressing units, suitable openings 47 being provided for the reception thereof. The press-frame may be adapted for any desired number of pressing units but in the form shown is designed to carry twelve vertical units in a circular arrangement.

The pressing units

Each pressing unit is designed for holding a column of heels and is preferably made up of three vertical guide members for retaining the heels in column formation, two being adapted to engage the breast of the heel and the third the rear (Fig. 5). The two front guide members 50 may be made of angle iron, right-angled in cross-section, and the rear guide member 51 of channel iron, U-shaped in cross-section, to bear at two points on the rear of the heels. In mounting the pressing units in the two disks 39 the two guides 50 of each unit are each arranged with one leaf engaging the straight outer edge of the opening 47 and the other leaf is partially cut away at each disk and projects into a slot in the disk perpendicular to the edge of the opening. The uncut portions of the other leaf of each guide thereby extend over the top and bottom faces

of each disk which locks the guide on the disks against vertical movement. Screws 54 (Fig. 16) may be threaded into the edges of the disks to hold the guide in engaging position with the front edge of the opening. The guides 50 are permanently fixed in place and are of sufficient width to engage each one end of the breast of the heel whatever its size may be. The U-shaped rear guide 51 fits within the squared rear portion of the openings 47 in the two disks and is supported by two rack-bars 55 (Fig. 5), each slidably mounted in a radial recess 56 cut in the under face of one of the disks, the outer ends of said bars being fastened to the center back face 80 of the guide. Meshing with each rack bar 55 is a pinion 58 set within a circular recess also formed on the under face of the disk and the two pinions are mounted on a vertical shaft 60 passing through said disks and a circular boss 61 formed on the upper face of each disk to serve as additional bearing surface for the shaft. A circular cover plate 59 is fastened to the under face of each disk to hold the rack bar and pinions within their respective recesses. The guide 51 is adjusted toward and from the two fixed guides 50 to suit various sizes of heels by turning the shaft 60 to rotate the pinions and move the rack bars and for this purpose the upper or lower end of the shaft may be squared or provided with a pin to receive a wrench or other turning device.

For holding the column of heels in the pressing unit under constant pressure the top opening of the unit is restricted and the bottom opening of the unit is provided with suitable spring latches for holding the bottom of the column of heels. The top opening is not sufficiently restricted to prevent the top heel being pushed out by the pressure exerted in the process of inserting an additional heel in the bottom opening of the unit and thereby raising the entire column of heels a distance equal to the thickness of one heel. One form of means for restricting the top opening is shown in Fig. 6 comprising two knife edges so adjusted as to bear against the two opposite sides of the topmost heel. Preferably, these knife edges are sufficiently long to engage two or more heels and are so adjusted that the edges penetrate the heels to a slight extent thereby requiring a considerable pressure to force the topmost heel upwardly and out of the unit. When the units are closely arranged, a single plate 65 (Figs. 6 and 7) intermediate each two adjacent units may be used in place of two plates and may be provided with a knife edge 66 on each side. The plate 65 may be fastened by a screw 69 to a block 70 which in turn is held in place by being fastened to two double right-angled brackets 71 by screws 72, the outer ends of said brackets being fastened by screws 73 to the upper ends of the guide members 50.

For supporting the column of heels in the pressing unit three latches are provided for engaging the bottom surface of the lowermost heel, two being arranged in the breast 5 of the heel and one at the rear. The rear latch 80 (Fig. 17) is secured by rivets 81 to the lower end of the spring member 82 fastened to the channelled guide member 51, the latch being normally held in an inward position by the spring with its nose in position to engage the rear portion of the lowermost heel and to support it, the end of the latch 84 being turned outwardly through an opening 85 in the guide member 51 to serve as a 10 finger piece for retracting the latch when desired. The two front latches 86 are each pivoted at 87 and have a triangular nose portion 88 for supporting the front portion of the lowermost heel. The latch is held in 15 operative position by a spring 90.

The nose portions of all three latches are inclined in order that when a heel is pressed upwardly into the pressing unit the latches are automatically retracted by the heel until 20 it has passed by the nose portions when they are all thrown into operative positions by their respective springs. The operation of pressing the heel up into the bottom of the pressing unit causes the column of heels to 25 be moved upwardly and the topmost heel to be forced out past the knife edges and freed therefrom.

An upwardly extending spring 92 (Fig. 17) is secured to the upper portion of the 30 guide member 51 on its inner face for bearing against the rear curved ends of the heels to hold them in a forward position with their breasts against the guides 50 at the discharge end of the unit. This is necessary when 35 wedge-shaped heels are being pressed as will be explained hereinafter.

Extending upwardly from the top of the unit is a discharge runway through which the heels released from the pressing unit 40 travel before being discharged into a suitable pipe or other conduit (not shown) located above the feeding station. The pressing unit should be equipped to take care of wedge-shaped heels and it is necessary to 45 discharge the wedge-blocks at the top of the unit as will hereafter be explained and for that reason the pressed heels are carried upwardly beyond the point of the wedge-block discharge in order to permit the installation 50 of a fixed pipe or chute for directing the heels into a convenient receptacle at one side.

The discharge runway may be formed in any suitable manner as for instance by three 55 guide members in arrangement similar to the guides 50 and 51. A flat guide member 100 (Figs. 16 and 17) is secured by screws 101 to the outer face of the U-shaped guide 60 51 and is bent outwardly to direct the heels upwardly and outwardly for discharge. The two front guide members 103 are right-an-

gled in cross-section but have the front flanges 105 extended downwardly to be secured to the brackets 71 (Fig. 6) with a wedge-block rail referred to hereinafter. The lower end of each front guide 103 is held fixed on the screw 72 between the block 70 and wedge-block rail. The upper portions of the guide 103 are steadied by being connected together by a plate 107 fastened to the front flanges by screws 109 and the top edge 110 of the plate is bent outwardly approximately parallel with the top edge of the back guide member 100 for discharging the pressed heels into the conduit. 70 75 80

Frame rotating means

For rotating the pressing unit frame between feeding operations a space equal to the distance from center to center between adjacent units so that the pressing units may be brought up to the feeding station in a continuous sequence any suitable means may be provided and one such is shown comprising the following (Figs. 2 and 10). A ratchet-disk 120 is mounted upon the frame-shaft 37 between the base plate and the sub-base plate and is provided with a hub portion secured to said shaft by a set-nut 122. The periphery of the ratchet-disk has cut therein notches 124 having side walls converging 95 slightly inwardly corresponding in number to the number of pressing units on the frame and being equally spaced apart. Above the ratchet-disk is loosely mounted an arm 126, the pivoted end of which is in the form of a collar 127 to enclose the shaft 37 and the free end of which is connected by a rod 128 to the upper end of an arm 130 pivotally mounted at its lower end on a lug 132 on the sub-base plate. A roll 133 carried by the arm 130 is held in engagement with the periphery of a cam 134 by a spring 135 under tension connected at one end to a pin 136 in the arm and at the other end to an eye 138 on the sub-base plate. The connecting rod 128 is threaded at its ends into universal joints 140 by means of which it is connected to the two arms 126 and 130 in such a manner as to transmit motion from the arm 130 to the arm 126 which move in planes perpendicular to each other. Adjustment in the relation of the two arms to each other may also be made by rotating the rod so that it acts as a turn-buckle between the two universal joints 140. The cam 134 is fixed upon the main shaft 142 of the machine rotatably supported in upright brackets or standards 144 secured by bolts 145 to the sub-base plate 35 (Figs. 1 and 2). 100 105 110 115 120 125 130

Pivotedly mounted upon the arm 126 on a pin 151 near its end is an index pawl 150 having a laterally turned nose adapted for engaging the notches 124 in the ratchet-disk 120 and normally held in an inward locking position by a spring 152 under tension 130

fastened between an eye 153 on the arm 126 and to a pin 154 on the pawl. The rotation of the main shaft and cam pivotally oscillates the two arms 130 and 126 and on the 5 forward movement of the arm 126, it, through the instrumentality of the pawl, rotates the ratchet-disk and frame one step. On the backward stroke the inner edge of the nose of the pawl being oblique the pawl slips 10 out of the notch and is retracted with the arm to the next succeeding notch into which its nose is forced when reached by the spring 152.

In order to lock the frame in exact position in relation to the feeding mechanism, a keeper-pawl 160 is pivotally mounted on a pin 161 set in the top of a standard 162 on the sub-base plate. The nose of this pawl is shaped to fit exactly the notches 124 on 20 the ratchet-disk and is held in full inward position in the notch by a spring 164 under tension connected to pins 165 in the collar 127 and pawl 160. The sides of the nose of the pawl and of the notches being oblique, 25 the action of the spring 164 tends to force the nose into the full depth of the notch and thereby centers the frame exactly in feeding position. For withdrawing the nose of the pawl from the notch to permit the ratchet-disk to be fed forward, the rear end of the pawl is extended into position to be engaged by a cam 168 on the main shaft 142, which cam is so shaped that it throws the nose of the keeper-pawl out of the notch engaged by 30 it at the proper time and allows the pawl to return to normal position during the feeding movement of the ratchet-disk to engage the next succeeding notch.

When the machine is started in operation 40 if the pressing units are empty it is preferable that each pressing unit should be completely filled with heels before feeding into the next unit. This is necessary in order to develop pressure in the unit as soon as possible since the heels are loosely held therein until the column is built up to the top where the pressure is developed by the restrictive action of the knife-edges. In the ordinary 45 operation of the machine the index-pawl rotates the frame after each feeding operation and to hold the frame in one position during a succession of feeding movements, I provide means whereby the index pawl may be rendered inoperative when desired.

55 In Figures 3 and 4 is shown one form of means for attaining this end. A pin 170 is threaded into the pivoted end of the pawl 150 and is cut away on one side to receive on a pin 172 a latch 173 which normally hangs on 60 the pin 170 in the position shown by broken line in Fig. 4. A pin 175 is threaded into the arm 126 in position to be engaged by and locked in the latch when the latter is turned laterally upwardly as shown by full lines in 65 Fig. 4, the pin 175 being slightly recessed to

receive and hold the latch in place. In Fig. 3 the pawl is shown locked in an inoperative position with its nose out of engagement with the ratchet-disk so that movements of the arm 126 have no effect upon the ratchet-disk and the pressing unit frame remains stationary so long as the pawl remains in that condition.

Feeding means

75 As my machine is primarily designed to be used in connection with a heel making machine in order to press the heels immediately upon the conclusion of the assembling of the lifts into heel form and while the adhesive is still fresh, the feeding means includes means for removing the heels from the assembling element of the heel making machine to the feeding station and means at the feeding station for feeding the heels upwardly into the bottoms of the pressing units.

80 In combining the two machines, the conveyor of the heel making machine is extended to run over the top of the base-plate 33 of the table frame of the heel-press, suitable 85 means being provided for guiding it thereacross. The conveyor as shown comprises two endless parallel sprocket chains 180 running over a pair of sprocket-wheels 182 at each end thereof and a series of heel supporting plates 184 fastened thereto (Figs. 1 and 14). Each heel plate is secured by welding or otherwise to an under-plate 186 having downturned sides 187 riveted to the 90 links of the sprocket-chains by the pivotal 95 rivets 188. For guiding the conveyor on the base plate, a U-shaped guiding member 190 having its sides turned upwardly to fit into the double links of the sprocket-chains is secured to the top face of the base-plate. The 100 assembled heels 192 (Fig. 1) are carried by 105 the conveyor across the top of the table frame to a point from which they are transferred to the feeding station.

110 Any suitable means may be provided for moving the heels from the conveyor to the feeding station and one such means is shown comprising a member adapted for lateral reciprocation in relation to the conveyor for pushing the heels therefrom. This member 115 is in the form of a rack-bar 200 (Figs. 2, 8 and 14) mounted for horizontal reciprocation in an upright standard 202 provided with ears 203 for fastening it to the top face of the base-plate by bolts 204. On its forward end 120 the rack-bar has a head 206 with a vertical face for engaging a heel on the conveyor and pushing it off the conveyor laterally and to the means for feeding the heel upwardly into a pressing unit. A trough guide 208 fastened to the standard 202 by bolts 210 (Figs. 2 and 14) extends outwardly to receive and support the other end of the rack-bar on its 125 rearward movement. The trough 208 may be provided with a cover 209.

For reciprocating the rack-bar a pinion 212 (Fig. 8) is fixed to the top end of a short vertical shaft 214 rotatably mounted in the standard 202 and extending through the base-
 5 plate and having a smaller pinion 216 keyed to its lower end meshing with a gear 218 having a hub 220 to receive a pin 221 set in the lower face of the base-plate. A lug 222 on the gear adjacent its periphery receives a
 10 headed pin 223 for connecting one end of a universal connecting rod 224 to the gear and the other end of said rod is pivotally connected to the upper end of an arm 226 which is in turn pivotally connected at its lower end
 15 to a lug 227 on the sub-base plate. Near its upper end the arm carries a roll 228 for engaging a cam-path 230 in a cam 232 fixed on the main shaft 142. The rotation of the main shaft and cam oscillates the arm to turn
 20 the gear and through the pinions to reciprocate the rack-bar thereby pushing a heel from the conveyor to the feeding member on each revolution of the main shaft. A cover 233 conceals the top pinion 212.
 25 For preventing heels on the conveyor being carried beyond the head of the rack-bar, a stop-plate 240 is arranged transversely the conveyor to block the movement of the heels and to hold them in position to be engaged by
 30 the pushing member. Generally, however, the machine is so timed that the heels are moved off the conveyor before they actually reach and engage the stop-plate so that it usually serves only for emergencies and to
 35 insure actual stoppage when necessary. For removing the stop-plate, if desired, it is mounted on a pin 242 set transversely in and headed over the end of an arm 244 which is pivotally mounted at its other end on a screw
 40 pin 245 threaded into the standard 202 (Figs. 2 and 14) and a stop-screw 246 also threaded into the standard 202 limits the downward movement of the arm 244 and holds the stop-plate slightly above the top surface of the conveyor.
 45 The arm may be recessed to fit the stop-screw 246 and a washer 247 may be utilized for holding the arm and stop-plate exactly vertical. By means of this construction the stop-plate may be moved out of an
 50 operative position by turning the arm 244 around its pivot point and over to the outer side of the standard 202.
 55 Forming a bridge between the conveyor and the feeding plunger is a space-block 250 provided with a top-plate 252 which is preferably of brass since the adhesive binding the heel lifts together is less likely to adhere to the surface of brass, and thereby interfere with the feeding operations. The space-block is fastened in place on the top of the base-plate is fastened in place on the top of the base-plate and is of such height that the top surface of the brass top-plate is just a shade lower than the top surface of the heel-
 60 plates 184 of the conveyor. In plan the
 65

space-block is U-shaped to permit the feeding plunger to move in the space between the arms.

For centering the heels as they are moved onto the feeding plunger, any suitable means may be provided and one such is shown in Figures 13, 14 and 15. Two side-plates 254 are secured on edge on the two arms of the space-plate and on the top of each side-plate is fastened an arrow plate 256 extending toward the conveyor, which two plates form a foundation for the wedge-block magazine to be described hereinafter.

Two centering wings 260 each having a recessed block 262 secured adjacent one end thereof are loosely mounted on their longitudinal edges on the space-block 250 on vertical pins 264 loosely mounted in the plates 256 and base plate 33. The upper ends of the pins are turned over to engage the top faces of the plates 256. The wings are loosely mounted on the pins 264 which lie in the recesses in the blocks 262 (Fig. 15) so that they turn freely thereon. For regulating the space between the forward ends of the wings 260 adjusting screws 266 are threaded one through each of the two side plates 254 and adapted to bear against the rear face of one of the wings adjacent its free end. The screws constitute stops to limit the opening movement of the two wings. A butterfly nut 268 is threaded on each screw for adjusting it in relation to its respective wing. In making this adjustment a space slightly less than the width of the heel is left between the ends of the two wings so that as a heel is pushed through between them with its curved rear portion forward, the wings tend to center the heel and to place it in correct position for feeding into a pressing unit.

For feeding heels into the pressing units, a vertical plunger shaft 270 (Fig. 9) is mounted in the base-plate 33 and sub-base plate 35 for longitudinal reciprocation and is provided with a head 272 for receiving and holding heels. In plan the head is approximately square and on its forward portion has two upright back-straps 274 against which the rear portion of the heel abuts when in position to be fed. Normally the top face of the head is on a level with the top face of the brass plate 252 so that the two form a level floor, the head of the plunger lying within and between the arms of the U-shaped space-block and brass-plate.

For reciprocating the plunger shaft a sleeved rack 276 is secured to the lower portion of the shaft above the sub-base plate by a set screw 277 which rack meshes with a gear 278 rotatably mounted on an upright standard 280 secured to the sub-base plate. The gear is keyed to a short shaft 282 rotatably mounted in an elongated bearing 283 formed on the head of the standard and to the other end of said shaft is fixed a crank arm

284 carrying a roll 286 engaging the periphery of a cam 288 mounted on the main shaft of the machine. A helical spring 290 mounted on the plunger shaft 270 between the sleeved rack 276 and the base plate 33 and under compression holds the plunger shaft downwardly. By manipulation of the set screw 277 the plunger shaft may be vertically adjusted in the sleeved rack 276 for securing an absolute register of the top face of the head with the top face of the brass plate on the space-block when the plunger shaft is in a normal downward position with the lower end of the sleeved rack engaging the top face of the sub-base plate.

The foregoing construction comprises all the parts of the heel press necessary for the pressing of ordinary flat heels in which the top and bottom faces are parallel. In the pressing of wedge shaped heels in which the top and bottom faces of the heels are oblique to each other and in which the heels are thinner at their breast ends, additional means is required for securing a column formation within the pressing units and this result is attained by the use of wedge blocks interposed between the breast portions of adjacent heels. Since the machine is designed for automatic operation, the use of wedge blocks requires the provision of means for inserting a wedge block in position on every feeding movement and for the separation of the wedge blocks from the heels after they pass out of the pressing unit. One form of means for accomplishing this result is illustrated in the drawings comprising a fixed wedge block magazine located at the feeding station in position to deliver a wedge block to the feeding mechanism whenever a heel is inserted in a pressing unit and means whereby the wedge blocks on immersing from the top of the pressing unit are directed by suitable guides into the top of the wedge block magazine. In consequence, when the machine is arranged for pressing wedge-shaped heels every time a wedge block and heel is inserted in the bottom of a pressing unit a wedge block and heel are forced out at the top of the unit, the heel going in one direction and the wedge block being diverged in another direction into the wedge block magazine. In view of the facts that the wedge block magazine is fixed and the frame carrying the pressing units is rotatable, it is necessary to break and make the wedge block guiding connection between the magazine and the pressing unit at the feeding station just before and after each feeding movement of the frame respectively. For this purpose a gate is provided for bridging the interval between the wedge block magazine and that pressing unit which happens to be at the feeding station, the gate being automatically operated to bridge the gap upon the conclusion of each feeding movement of

the frame and to break the gap just before the frame is rotated the next step.

The wedge block may be made in any suitable form but as shown in perspective in Fig. 22 comprises a block 300 of elongated rectangular form having its central portion wedge-shaped in transverse-section and its two ends 302 of equal thickness transversely with parallel top and bottom faces, or in other words, having squared ends. 70 Each end of the block is provided with a cut-out portion or recess 304 adapted to receive guides or rails by means of which the wedge blocks are directed and caused to travel from the pressing unit to the magazine. 75

The wedge block magazine is made up of two upright rail members 308, each member being U-shaped on its inner side to receive the squared ends of the wedge blocks and to hold 80 said blocks in a vertical edgewise position within said magazine. These rail members may be made in any suitable manner as by using angle iron with a strip secured to one edge to form a guide U-shaped in cross section. The rails are set on end on the plates 256 and are each held in an upright position by a suitable angular support 310 (Figs. 13 and 14) fastened by bolts 312 to the ends of the plates 256 adjacent the conveyor and by 95 screws 314 to the rails.

As the column of heels travels upwardly in the pressing unit, the wedge-blocks between wedge-shaped heels 319 are naturally held in engagement with the guide members 50 (Fig. 100 17) because the bottom face of each heel lies in a horizontal plane and the top face is inclined downwardly toward the breast so that there is a tendency as the column is disturbed more or less on each feeding operation for the wedge-block to slide or to be pressed by the heel above it down the inclined top face of the heel against the two guide members 50.

On the top end of the wedge-block magazine is mounted a gate capable of a limited 110 pivotal movement into and out of engagement with wedge-block guiding means carried by each of the pressing units. The gate comprises two short lengths 320, U-shaped in cross-section, each length being provided 115 with an ear 323 which is connected by a pin 324 to a similar ear 325 on the upper end of each of the members 308. The two short lengths making up the gate are connected together by a cross-piece 326 corresponding to 120 a similar cross piece 328 connecting the upper ends of the magazine sides 308. At its upper end the member 320 is provided with a laterally extending rail 330. The gate when in operative position as shown in Fig. 125 17 is in engagement with a curved rail 332 which is secured (Fig. 6) by the screws 72 to the block 70 between the members 105 and the inner ends of the angle bracket 71, its lower end extending downwardly into the 130

- pressing unit in position to engage the end recesses in the wedge-blocks as they move upwardly in the unit. The upward movement of the column of heels carries the wedge-blocks upwardly until they are locked on the rails when they are forced over the curved portion of the rails; then slide downwardly by gravity into engagement with springs 333 arranged one on the under face of each rail 332. These springs hold the wedge-blocks clustered in the ends of the rails 332 until a sufficient number have gathered there for the pressure created by the upward movement of the heel column on each feeding of a heel 15 into the bottom of the unit to be transmitted therethrough when a wedge-block is forced off the end of the rails on each feeding movement and slides down into the magazine edge-wise.
- 20 For operating the gate at the proper times any suitable means for moving it pivotally to and from operative position may be employed, one such means being shown. The gate may be fastened by a key 334 (Fig. 17) 25 to the pin 324 and a universal joint 336 (Fig. 1) is keyed to the pin to turn in unison. The universal joint 336 is connected to a rod 338 to a second universal joint 340 keyed to an arm 342 (Fig. 12) pivotally mounted on a 30 bracket 344 secured by screws 346 to an upright 348 fastened to the base plate. The free end of the arm 342 is pivotally connected by a rod 350 to a compound lever 352 pivoted at 354 (Fig. 12), said arm carrying at its 35 other end a roll 356 held in engagement with a cam 358 (Fig. 2) by a helical spring 360 mounted on the end of the rod below the compound lever 352 which is compressed at all times. A block 361 held in place on the lower 40 end of the rod 350 by a set screw 362 may be adjusted to determine the pressure exerted by the spring. The rod 350 is also adjustable at its upper end by means of an adjusting nut 364 and a butterfly set nut 365. A spring 366 45 connected to the upright member 348 and to the arm 342 tends to hold the arm in an upward position and the gate in inoperative position.
- 50 In the operation of the wedge gate, the cam 358 is so timed in respect to the frame rotating mechanism that at the conclusion of the rotating movement of the frame carrying the pressing units the gate is thrown pivotally into engagement with the curved track 332 on the pressing unit at the feeding station and remains closed throughout the feeding movement. While the gate is closed, any wedge blocks dislodged from the pressure exerted by the spring 333 slide down 55 the rail 330 and drop edgewise into the magazine. Just before the frame is again rotated to bring the next pressing unit to the feeding station, the gate operating means 60 opens the gate by turning it pivotally on the pin 324 until the oblique end of the member 65 320 engages the upper end of the magazine at which point the gate stops and its upper end is sufficiently clear of the projecting rail 332 to permit the pressing unit to be moved freely. The gate is shown in closed oblique position in Fig. 17 and in open position in Fig. 20.
- 70 On the rear faces of the members 308 and extending downwardly to within a short distance of the bottom end of the magazine are 75 two stop springs 380, these two stop springs being also pivotally mounted on a cross bar 381 connecting the two upright members 308 of the magazine. Loosely mounted in each of the two upright members 308 is a horizontal pin 382, the rear end of which passes through a hole in the lower end of each of the springs near its horizontally turned end 383, that end of the pin being provided with a shoulder 384 for throwing the spring rearwardly when the pin is pushed rearwardly. Between the two stop springs 380 and fastened to the cross bar 381 is a central depending guide spring 386, the lower end of which normally lies within the wedge block magazine in a forward direction (Figs. 18 and 19). Pivotally mounted between the lower transverse portions of the brackets 310 is a switch member 388 extending upwardly and having a cut away portion 390 and provided with laterally extending ears 392 adapted to be engaged by transverse stops 394 on the brackets 310. For pivotally mounting the switch member 388, a cross bar 398 connects its lower ends and is provided with laterally 100 extending ears 399 mounted in suitable recesses formed in the lower surfaces of the brackets 310, so that the switch member has a free pivotal movement on said ears.
- 105 When the switch 388 is in an outward position the magazine is locked by the springs 380, the lower turned ends 383 of which hold the wedge blocks against further downward movement as shown in Fig. 18. In the normal operation of the machine, 110 when wedge blocks are being fed from the magazine, the switch 388 is thrown inwardly into the position shown in Fig. 19 and on its inward movement engages the inner end of the pin 382 and through the shoulder 384 throws out the two springs 380 thereby releasing the wedge blocks for further downward movement. To hold the switch in an inward position, a cam 400 may be mounted on the inner face of one of the brackets 310 115 and may be controlled by a cam lever 404 on the outside face of said bracket. The cam is semi-circular and so located that when in the position shown in Fig. 18 the switch may be thrown inwardly, one side of the cam being straight to permit the switch ear 392 to clear it. The cam 400 being loosely mounted, it is normally held in the position shown in Fig. 19 by gravity acting on the cam lever to hold it in vertical position as shown in 120
- 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

Fig. 14. To move the switch, in Fig. 18, the cam is shown in a position which will enable the switch to clear it but in that position the cam lever must be turned into the oblique position shown in broken lines in Fig. 14. As a matter of fact, however, it is unnecessary to operate the cam lever when throwing the switch into inward position because when pushed inwardly it will engage the straight side 402 of the cam and turn it sufficiently to clear it. To return the switch to outward position, however, manipulation of the cam lever 404 is necessary and a pin 405 may be provided to facilitate its manipulation. With the switch in inward position and the wedge blocks for downward movement, they then fall into horizontal position between the inner wall of the magazine and the switch member as shown in broken lines in Fig. 19, the spring 386 serving to direct the thick end of the wedge blocks as they fall into engagement with the switch member when it then drops into horizontal position. The spring 386 is sufficiently light so that the weight of the blocks throw it out to permit the front end of the blocks to pass by. The bottom wedge block when stopped normally rests upon the latches or shoulders 406 formed on the plates 256 which also serve as guide rails for directing the movement of the wedge blocks in their journey from the magazine to the feeding means.

The wedge blocks are fed from the magazine on each forward movement of the headed rack bar which pushed the heels from the conveyor, the head of the rack bar being just high enough to engage the center of the wedge block on its forward pushing movement and then pushes the wedge block out of the magazine along the guide rails 406 supporting the two ends of the wedge block so that at the end of the pushing movement of the rack bar the wedge block is supported above the breast portion of the heel in position to be pushed into the pressing unit with the heel on the upward movement of the feeding plunger.

When the machine is being started without wedge blocks in the magazine, the wedge blocks may be fed by hand into the top end of the magazine one at a time but for providing a convenient medium for automatically feeding wedge blocks to the machine until the magazine has been sufficiently filled to feed direct therefrom, a wedge block storage rack may be provided made up of two parallel rails 410 held together by suitable rods 414. Wedge blocks may be mounted flatwise in the rack as shown in Fig. 21, the inner of the rails 410 engaging the recesses in the end of the block to hold them thereon. A gate 412 may be pivotally mounted on the lower rod 414, the rod being offset in relation to the path of the wedge blocks so that by turning the gate outwardly into perpendicu-

lar position to the rails the wedge blocks will slide downwardly on the rails and drop off the end of the storage rack. The two upper ends of the rails 410 are each provided with an inwardly projecting pin 416 to enable the rack to be hung in two perforated ears 419 mounted on the outer face of the wedge block magazine (Fig. 1). When so hung, the storage rack occupies the position shown by the broken lines of its lower end in Fig. 18 and the turning of the gate 412 into open position with the switch 388 in outward position permits the wedge blocks carried by the rack to drop down until the bottom block engages the guide rails 406. Thereafter as the bottom block is fed rearwardly the column of blocks moves downwardly from the rack. This is continued until the machine has been loaded and until the magazine is filled after which the rack is removed, the switch 388 turned inwardly and the wedge blocks fed from the magazine.

The storage rack also is of advantage in unloading the pressing units. For instance, if the machine is going to be transferred from wedge shaped heels to flat heels, the rack is hung on ears 420 carried by the uprights 50 and the latch 80 and springs 88 are then pressed outwardly to permit the column of heels to drop out of the pressing unit. As the column drops out the recesses on the wedge blocks engage the rails 410. As a general rule, the entire column drops down with the wedge blocks on the storage rack and the heels are then pressed out completing the operation of unloading a pressing unit and loading the storage rack.

My heel press may be used either alone or in connection with a heel making machine but its latter use has many advantages one of the most important of which is that the heels are pressed immediately after being assembled and while the adhesive is fresh and therefore at a time when the pressure is most effective for producing a uniformly dense and strong product. When used alone, the heels may be supplied to the feeding means at the feeding station either by hand or from any suitable source of supply.

The operation of the heel press is simple. When flat heels are being pressed in conjunction with a heel making machine or heel assembling machine the entire product of the latter machine is handled by the former. In the foregoing description of one form of my invention, I have referred to the heels delivered by the conveyor of the heel making machine as single heels but this is not strictly correct because some machines assemble and deliver two or more heels in heel piles. For instance, when heels are composed of only two to four lifts, a heel making machine of the construction of my patent, hereinbefore referred to, may deliver heel piles made up of two or three or even more heels and this

- is accomplished by omitting the application of adhesive on certain lifts. If the heel making machine has twelve lift supplying units, four heels of three lifts each or three heels 6 of four lifts each or six heels of two lifts each may be included in each heel pile delivered by the conveyor merely by omitting the application of adhesive to certain lifts in each pile. So far as my heel press is concerned, the heel pile on the conveyor is treated the same whether it contains one, two, or more heels and after the pile has been pressed it will then separate into the several heels of which it is made up. It is to be understood, therefore, that each feeding operation forces a heel pile into a unit which pile may contain one or more heels dependant upon the application of the adhesive. This also applies to wedge shaped heels because the 20 wedge blocks are designed for thick heels and will take care of a plurality of thin heels made of a smaller number of lifts. The wedge block may, however, be formed for the use to be made of them.
- 25 The heel press may be operated from any suitable source of power and on one end of the main shaft is mounted a gear wheel 500 for rotating the same. A hand wheel 502 may be fixed to the other end of said shaft 30 for turning it over by hand when necessary. A feeding movement occurs on each complete revolution of the main shaft and the main shaft should be timed to correspond to the delivery speed of the heel making machine.
- 35 The cycle of operation is as follows. The conveyor rotates continuously and when a heel pile on the conveyor approaches a point in line with the headed rack-bar the latter is thrown forward and pushes the heel pile 40 off the conveyor and onto the plunger head at the feeding station the rear portion of the heel pile engaging the stops on the plunger head. If wedge shaped heels are being pressed the rack-bar head engages the lowest 45 wedge block in the wedge-block magazine, pushes it along the rails and over the plunger head. The rack-bar is then retracted. The plunger carrying the heel pile next moves upwardly and forces the heel pile between 50 the latches, throwing them outwardly, into the bottom or inlet end of the pressing unit. This action raises the entire column of heels in the unit and forces a heel pile out of the restricted outlet end of the unit. If a wedge 55 block is in the line of upward movement, the heel pile carries it up with it into the pressing unit. The throw of the plunger should be just sufficient to push the heel pile upwardly to a point to release the latches so that they 60 will be forced back by their respective springs into locking position under the bottom of the heel pile to lock the column of heels in the unit. The plunger then moves downwardly.
- 65 On each feeding movement a heel pile emerges from the pressing unit at the feed-

ing station and tumbles into a chute arranged there for directing pressed heels into a suitable receptacle, if wedge-blocks are used one is directed into the wedge block magazine to compensate for the one fed out at the bottom of the magazine. The wedge block gate is then thrown outwardly to release the pressing unit and the frame is rotated one step to bring the next succeeding unit to the feeding station and the gate to close the gap to the block magazine is thrown inwardly. By this time, the conveyor has moved sufficiently to bring another heel pile into register with the headed rack-bar when the foregoing cycle of operations is repeated.

The length of time that a heel pile remains under pressure will depend upon a number of conditions such as the number and size of the units and the speed at which the press operates but if it is operated continuously a heel pile will remain under pressure for a period of time equal to the interval between feeding operations multiplied by the total number of heels in the press. For instance, in a press having twelve units, each holding fifty heel piles, and operating at a feeding rate of thirty heel piles per minute, each heel pile will be subjected to pressure for twenty minutes. By employing an adhesive which will set and harden within that period, the 95 heels are turned out in a finished state so far as the pressing is concerned.

The machine of my invention has many advantages. It presses heels rapidly and efficiently and produces a product which is even and uniform. It operates upon wedge shaped heels as easily as upon flat heels and with equally good results. It is easily adjusted to different sizes and shapes of heels and can be operated in conjunction with a 100 heel making machine without requiring any attention for the transfer of heels from one machine to the other.

It is further to be observed that my invention effects a great saving in space for 110 it may be embodied in a very compact machine which adds but little to the space occupied by a heel making machine and effects a large saving in labor due to its automatic operation and to the fact that it requires little 115 or no supervision or attendance other than the operator of a heel making machine. The heels produced are better and more accurate and much cheaper.

The foregoing description is merely illustrative of my invention since it may be embodied in various forms of construction other than that shown without departing from the spirit thereof.

What I claim is:—

1. In a heel press, the combination of a rotatable frame, a plurality of vertical heel pressing units fixed on said frame, reciprocating means for moving heels one at a time onto a plunger, means for reciprocating said 120

- plunger to force said heels into said units and means for rotating said frame to bring said units successively into register with said plunger to receive a heel.
- 5 2. In a heel press, the combination of a frame, a plurality of vertical heel pressing units mounted on said frame, each of said units being adapted for receiving and holding under pressure a column of heels, means for transferring one heel at a time from the conveyor of a heel making machine to a station under said frame, means for rotating said frame in a step-by-step manner to bring a unit in register with said station on each operation of said rotating means and means at said station for forcing a heel into the unit at said station. 70
- 10 3. In a heel press, the combination of a rotatable frame, a plurality of heel pressing units vertically mounted on said frame, each of said units being adapted for receiving and holding a column of heels, means for restricting the two ends of each unit to hold the heels therein under pressure, a vertically reciprocating plunger for forcing heels one at a time into the bottom end of each of said units in sequence and means for rotating said frame to bring said units successively into register with said feeding means. 75
- 15 4. In a heel press, the combination of a rotatable frame, a plurality of vertical heel pressing units mounted on said frame and equally spaced apart, vertically reciprocating means located at a fixed station for feeding heels into the bottoms of said units one at a time and means for rotating said frame in a step by step manner one step after each feeding movement to bring the pressing units into successive register with the feeding means; said rotating means being capable of adjustment to hold a unit at the feeding station during a succession of feeding operations. 80
- 20 5. In a heel press, the combination of a rotatable frame, a plurality of vertical heel pressing units mounted on said frame, means located at a fixed station for feeding heels into the bottoms of said units, means for rotating said frame one step after each feeding movement to bring the next unit into register with the feeding means; said rotating means including a ratchet-disk provided with peripheral notches equally spaced apart, an arm pivotally mounted, a pawl carried on the end of said arm and adapted to engage said notches and cam operated means for oscillating said arm to advance said ratchet-disk one step at a time. 85
- 25 6. In a heel press, the combination of a rotatable frame, a plurality of vertical pressing units mounted on the periphery of said frame and equally spaced apart, means beneath said frame for feeding heels into the bottom ends of said units one at a time, said means being located at a fixed station and cam operated means for rotating said frame in a step by step manner to bring said pressing units in sequence to said feeding station. 90
- 30 7. In a heel press, the combination of a rotatable frame, a plurality of vertical pressing units mounted on the periphery of said frame and equally spaced apart, means beneath said frame for feeding heels into the bottom ends of said units one at a time, said means being located at a fixed station, and cam operated means for rotating said frame in a step by step manner to bring said pressing units in sequence to said feeding station; said rotating means being so arranged as to be capable of being thrown out of operation in order to maintain said pressing units at said feeding station for a succession of feeding operations in order to permit said feeding units to be completely filled in sequence when the machine is being started in operation. 95
- 35 8. In a heel press, the combination of a frame for holding a plurality of vertical pressing units and means for rotating said frame in a step by step manner, said means including a ratchet-disk provided with a plurality of peripheral notches, a pawl for engaging said notches and cam operated means for moving said pawl in a forward direction one notch at a time. 100
- 40 9. In a heel press, the combination of a shaft rotatably mounted, a frame fastened to said shaft, a plurality of vertical pressing units carried by said frame, means located at a fixed station for feeding heels into the bottom end of one of said units at a time, a ratchet-disk fixed on said shaft and provided with a plurality of equally spaced peripheral notches corresponding in number to the number of said pressing units and means for engaging said notches to rotate said frame in a step by step manner to move said pressing units in a continuous sequence to said feeding station. 105
- 45 10. In a heel press, the combination of a frame for holding a plurality of vertical pressing units, means for rotating said frame in a step by step manner and cam-operated means for locking said frame in position at the end of each feeding movement, said rotating means being capable of being rendered inoperative at the will of the operator to hold said frame stationary so long as said rotating means remains inoperative without otherwise interfering with the operation of the machine. 110
- 50 11. In a heel press, the combination of a frame for holding a plurality of vertical pressing units, means for rotating said frame in a step by step manner and cam-operated means for centering said frame and locking it between the feeding movements, said rotating means being capable of being rendered inoperative at the will of the operator to hold said frame stationary so long as said rotating means remains inoperative without 115
- 55 12. In a heel press, the combination of a frame for holding a plurality of vertical pressing units, means for rotating said frame in a step by step manner and cam-operated means for centering said frame and locking it between the feeding movements, said rotating means being capable of being rendered inoperative at the will of the operator to hold said frame stationary so long as said rotating means remains inoperative without 120
- 60 13. In a heel press, the combination of a frame for holding a plurality of vertical pressing units, means for rotating said frame in a step by step manner and cam-operated means for centering said frame and locking it between the feeding movements, said rotating means being capable of being rendered inoperative at the will of the operator to hold said frame stationary so long as said rotating means remains inoperative without 125
- 65 14. In a heel press, the combination of a frame for holding a plurality of vertical pressing units, means for rotating said frame in a step by step manner and cam-operated means for centering said frame and locking it between the feeding movements, said rotating means being capable of being rendered inoperative at the will of the operator to hold said frame stationary so long as said rotating means remains inoperative without 130

otherwise interfering with the operation of the machine.

12. In a heel press, the combination of a frame for holding a plurality of vertical pressing units, means for rotating said frame in a step by step manner and a keeper-pawl for centering and locking said frame between the rotating movements.

13. In a heel press, the combination of a 10 rotatable frame, a plurality of vertical pressing units mounted around said frame and equally spaced apart, means located at a fixed station for feeding heels into the bottom end of one of said units at a time, means for rotating said frame in a step by step manner to bring said pressing units in sequence to said feeding station and cam-operated means for locking said frame against rotation at said feeding station.

14. In a heel press, the combination of a frame, a plurality of heel vertical pressing units mounted on said frame and spaced equally apart, means located at a fixed station for feeding heels into the bottom end 25 of one of said units at a time, means for rotating said frame intermittently to bring said units in sequence to said feeding station and cam-operated means for locking said frame against rotation during the feeding 30 movements.

15. In a heel press, the combination of a frame for holding a plurality of vertical pressing units, means for rotating said frame in a step by step manner, said means including a ratchet-disk provided with a plurality of peripheral notches, a pawl for engaging said notches, cam-operated means for moving said pawl in a forward direction one notch at a time and means for locking said 35 frame against rotation between said rotating movements.

16. In a heel press, the combination of a frame, a ratchet-disk mounted on said frame and provided with a plurality of peripheral notches, a pawl for engaging said notches, cam-operated means for moving said pawl in a forward direction one notch at a time and a keeper-pawl for engaging said notches to lock said frame against rotation between the 45 forward movements of said first-mentioned pawl.

17. In a heel press, the combination of a rotatable frame, a plurality of vertical heel pressing units mounted on said frame, means located at a fixed station for feeding heels into said units, a ratchet-disk mounted on said frame provided with peripheral notches equally spaced apart and corresponding in number to the number of 55 units on said frame, a pawl for engaging said notches, means for reciprocating said pawl a distance equal to the center from center distance between adjacent notches and a second pawl pivotally mounted at a fixed 60 point and adapted to engage said notches

for locking said ratchet-disk between the rotating movements.

18. In a heel press, the combination of a frame, a plurality of vertical heel pressing units mounted on said frame, means for moving said frame to bring said units successively to a feeding station, means for pushing heels from the delivery end of a heel making machine to said feeding station and means for feeding the heels so delivered into said 70 pressing units.

19. In a heel press, the combination of a frame, a plurality of vertical heel pressing units mounted on said frame, means for moving said frame intermittently for bringing said units in sequence to a feeding station, means for pushing heels from the conveyor of a heel making machine to said feeding station and means for feeding heels into said 75 units.

20. In a heel press, the combination of a frame, a plurality of vertical heel pressing units mounted on said frame, means for rotating said frame to bring said units in succession to a fixed feeding station, reciprocating means for pushing heels from the conveyor of a heel making machine to said station and means for feeding said heels into said 80 units.

21. In a heel press, the combination of a frame, a plurality of vertical heel pressing units mounted on said frame, means for rotating said frame to bring said units in sequence to a feeding station, means for feeding wedge shaped heels from a heel making machine to said station, means for feeding said wedge shaped heels into said pressing units and means for inserting a wedge block between adjacent heels on each feeding 85 movement.

22. In a heel press, the combination of a pressing unit for holding a column of heels, means within said unit for holding said column under constant pressure, means for feeding heel piles into said unit, a wedge block magazine located adjacent said pressing unit for holding a supply of wedge blocks, means for throwing a wedge block in advance of the heel pile in order that the wedge block will be inserted in said pressing unit between adjacent heel piles and means whereby each wedge block is guided into the top of the said magazine as it emerges from the top end of said unit.

23. In a heel press, the combination with a wedge block magazine of a pressing unit for holding a column of heels, said unit having end openings, means for feeding wedge shaped heel piles into one end of said unit, means for inserting between said wedge piles in said unit wedge blocks for equalizing the thickness of the column of heels in the unit and means whereby each wedge block is guided into the top of the said magazine as it emerges from the top end of said unit.

24. In a heel press, the combination with a wedge block magazine of a pressing unit for holding a column of heels, means in said unit for subjecting said column to a constant pressure, means for feeding wedge shaped heel piles into said unit, means for inserting wedge shaped blocks between adjacent heel piles in said unit for equalizing the thickness of said column and means whereby each wedge block is guided into the top of the said magazine as it emerges from the top end of said unit. 70
25. In a heel press, the combination with a wedge block magazine of a pressing unit for holding a column of heels, means in said unit for holding said column under constant pressure, means for feeding heel piles into one end of said pressing unit, means for feeding wedge blocks into said pressing unit on each feeding operation of said heel piles, said means being adapted to be thrown out of operation when flat heels are being fed into said pressing unit and means whereby each wedge block is guided into the top of the said magazine as it emerges from the top end of said unit. 80
26. In a heel press, the combination of a pressing unit for holding a column of heels, a wedge-block magazine and means for guiding wedge-blocks from the top of said unit to the top of said magazine. 85
27. In a heel press, the combination of a top delivery pressing unit for holding a column of heels, a wedge-block magazine and a pair of guiding members for guiding wedge-blocks from the top of said pressing unit into the top of said magazine. 90
28. In a heel press, the combination of a top delivery pressing unit for holding a column of heels, a wedge-block magazine and a pair of guide rails for guiding wedge-blocks into the top of said magazine from the delivery end of said pressing unit. 95
29. In a heel press, the combination of a pressing unit for holding a column of heels, a wedge-block magazine, means for guiding wedge-blocks from one end of said magazine to the inlet end of said pressing unit and means for guiding wedge-blocks from the delivery end of said unit to the other end of said magazine. 100
30. In a heel press, the combination of a pressing unit for holding a column of heels, a wedge-block magazine, a switch for controlling the passage of wedge-blocks from said magazine and means for feeding heels to said pressing unit; said feeding means being adapted when said magazine switch is open to withdraw a wedge-block from said magazine in each feeding movement. 105
31. In a heel press, the combination of a pressing unit for holding a column of heels, a wedge-block magazine and means for feeding heels to said unit, said feeding means being provided with means for withdrawing a wedge-block from said magazine on each feeding operation. 110
32. In a heel press, the combination of a rotatable frame, a plurality of heel pressing units on said frame, means located at a station for feeding heels, a wedge-block magazine located at said station and a switch for diverting heels from said magazine to said feeding means. 115
33. In a heel press, the combination of a rotatable frame, a plurality of heel pressing units carried by said frame, means located at a station for feeding heels into the unit at said station, and a wedge-block magazine at said station, said feeding means being provided with means for withdrawing a wedge-block from said magazine on each feeding operation. 120
34. In a heel press, the combination of a rotatable frame, a plurality of heel pressing units carried by said frame, means located at a station for feeding heels into the unit of said station, a wedge-block magazine at said station for furnishing wedge-blocks to separate wedge-shaped heels in said units and means whereby said wedge-blocks after passing through said units are returned to said magazine. 125
35. In a heel press, the combination of a rotatable frame, a plurality of heel pressing units carried by said frame, means located at a station for feeding heels into the unit at said station, means for rotating said frame to bring said units in sequence to said station, a wedge-block magazine at said station and means whereby a wedge-block is fed to the unit at said station on each heel feeding operation. 130

- rotatable frame, a plurality of heel pressing units carried by said frame, means located at a station for feeding heels into the unit at said station, means for rotating said frame to bring said units in sequence to said station, a wedge-block magazine at said station, means whereby a wedge-block is fed to the unit at said station on each heel feeding operation, a bridge connecting said magazine to the unit at said station for permitting wedge-blocks discharged by said unit to fall into said magazine and means for operating said bridge to connect and disconnect said magazine with the unit at said station.
39. In a heel press, the combination with a rotatable frame carrying a plurality of pressing units and means for rotating said frame to bring said units in sequence to a fixed station of a wedge-block magazine at said station and means for connecting said magazine to the unit at said station for receiving wedge blocks therefrom.
40. In a heel press, the combination with a rotatable frame carrying a plurality of pressing units and means for rotating said frame in a step-by-step manner to bring said units in sequence to a fixed station of a block magazine fixed at said station and a bridge pivotally mounted on said magazine for connecting it to the unit at said station.
41. In a heel press, the combination with a rotatable frame carrying a plurality of pressing units and means for rotating said frame in a step-by-step manner to bring said units in sequence to a station, of a block magazine at said station, means pivotally mounted on said magazine for bridging the gap between said magazine and the unit at the station and means for operating said bridging means.
42. In a heel press, the combination with a rotatable frame carrying a plurality of pressing units and means for rotating said frame in a step-by-step manner to bring said units in sequence to a station, of a block magazine at said station, a block guiding member pivotally mounted on said magazine and means for automatically throwing said member into engagement with a pressing unit when it arrives at a station to permit blocks forced out of said unit to drop into said magazine.
43. In a heel press, the combination with a rotatable frame carrying a plurality of pressing units and means for rotating said frame in a step-by-step manner to bring said units in sequence to a station, of a wedge-block magazine for supplying wedge blocks to said units and a switch mechanism in said magazine for controlling the exit of blocks therefrom.
44. The combination with a heel making machine having an endless movable conveyor for delivering assembled heel piles, of a heel press comprising a rotatable frame, a plurality of pressing units carried by said

frame, means for rotating said frame in a step-by-step manner to bring said units in sequence to a feeding station, means for moving one heel pile at a time from said conveyor to said station and means for forcing said heel pile into the unit at said station.

45. The combination with a heel making machine having an endless movable conveyor for delivering assembled heel piles, of a heel press comprising a rotatable frame, a plurality of pressing units carried by said frame, means for rotating said frame in a step-by-step manner to bring said units in sequence to a station, means for pushing one heel pile at a time from said conveyor onto a plunger at said station and means for operating said plunger to force said heel pile into the bottom end of the pressing unit at the station.

46. The combination with a heel making machine having an endless moving conveyor for delivering assembled heel piles, of a heel press comprising a rotatable frame, a plurality of pressing units carried by said frame, means for rotating said frame to bring said units in sequence to a station, a reciprocating member for pushing one heel pile at a time from said conveyor onto a plunger head at said station and means for reciprocating said plunger to force said heel pile into the bottom end of the pressing unit at said station.

47. In a heel press, the combination of a rotatable frame, a plurality of units for holding heels under pressure mounted on said frame, means for feeding heels into one of said units at a time and means for rotating said frame in a step-by-step manner to bring said units successively into register with said feeding means, said rotating means being adapted to be thrown out of operation at the will of the operator to hold a unit in register with said feeding means for a succession of feeding operations.

48. In a heel press, the combination of a rotatable frame, a plurality of pressing units mounted on said frame, each adapted to hold a column of heels, means located at a fixed station for feeding heels into one of said units at a time and means for rotating said frame in a step-by-step manner to bring said units successively into register with said feeding means, said rotating means being adapted to be thrown out of operation at the will of the operator to hold a pressing unit at the feeding station for a succession of feeding operations.

49. In a heel press, the combination of a rotatable frame, a plurality of heel pressing units mounted on said frame in a circular arrangement, means located at a fixed station for feeding heels into one of said units at a time and means for rotating said frame after each feeding movement to bring the next unit into register with said feeding

means, said rotating means being adapted to be thrown out of operation at the will of the operator to hold a pressing unit at the feeding station for a succession of feeding operations.

5 50. In a heel press, the combination of a frame, a plurality of heel pressing units mounted on said frame, means located at a fixed station for feeding heels into said units and means for moving said frame to bring said units in a continuous sequence to said feeding station, said moving means being adapted to be thrown out of operation at the will of the operator to hold a pressing unit 10 at the feeding station for a succession of feeding operations.

20 51. In a heel press, the combination of a frame, a plurality of pressing units mounted in said frame and means for rotating said frame in a step-by-step manner, said means including a ratchet-disk provided with a plurality of peripheral notches, a pawl for engaging said notches and means for moving said pawl in a forward direction one notch 25 at a time, said pawl being adapted to be fastened in inoperative position at the will of the operator.

30 52. In a heel press, the combination of a frame for holding a plurality of pressing units and means for rotating said frame in a step-by-step manner, said means being adapted to be thrown out of operation at the will of the operator to hold said frame in a fixed position without otherwise interfering with the operation of the machine.

35 53. In a heel press, the combination of a pressing unit for holding a column of heels, means for feeding heels into said unit, a wedge block magazine and means for delivering 40 to said feeding means from said magazine a wedge block on each feeding operation.

45 54. In a heel press, the combination of a pressing unit for holding a column of heels, means for feeding heels into said pressing unit, a wedge block magazine and means for controlling the delivery of wedge blocks from said magazine to said feeding means.

50 55. In a heel press, the combination of a pressing unit for holding a column of heels, means for feeding heels into said unit, a wedge block magazine adapted for delivering wedge blocks to said feeding means and a switch for controlling the delivery of wedge blocks from said magazine.

55 56. In a heel press, the combination of a pressing unit for holding a column of heels, means for feeding heels into said unit, a magazine for holding a supply of wedge blocks and 60 a manually operated switch for controlling the delivery of wedge blocks from said magazine, said switch in one position permitting the automatic delivery to said feeding means of a wedge block on each feeding operation 65 and in another position preventing any de-

livery of wedge blocks from said magazine.

57. In a heel press, the combination of a frame, a plurality of pressing units mounted on said frame, means for feeding heels into said units in rotation and means adapted for feeding a wedge block on each feeding operation, said means being adapted to be thrown into and out of operation at the will of the operator.

70 58. In a heel press, the combination of a rotatable frame, a plurality of heel pressing units mounted on said frame, means for feeding heels into said units, means for feeding a wedge block to said feeding means on each feeding operation and means for throwing said wedge block feeding means into and out of operation at the will of the operator.

75 59. In a heel press, the combination of a rotatable frame, a plurality of heel pressing units mounted on said frame, means for feeding heels into said units, means for feeding a wedge block to said feeding means on each feeding operation and a switch for throwing said wedge block feeding means into and out of operation at the will of the operator.

80 60. The combination with a heel making machine having a movable conveyor for delivering assembled heel piles, of a heel press comprising a plurality of pressing units, means for feeding heel piles into said units, means for feeding a wedge block to said feeding means on each feeding operation and means for throwing said wedge block feeding means out of operation at the will of the operator.

85 61. The combination with a heel making machine having a movable conveyor for delivering assembled heel piles, of a heel press comprising a rotatable frame, a plurality of pressing units carried by said frame, means for rotating said frame in a step-by-step manner to bring said units in sequence to a station, means for transferring one heel pile at a time from said conveyor to said station, means for feeding the heel pile at said station into the pressing unit thereat, means for feeding a wedge block to said feeding means on each feeding operation and means for throwing said wedge block feeding means out of operation at the will of the operator.

90 62. In a heel press, the combination of a rotatable frame, a plurality of pressing units carried by said frame, means for rotating said frame in a step-by-step manner and means for locking said frame against rotation between said steps; said rotating means being capable of being rendered inoperative at the will of the operator.

100 63. In a heel press, the combination of a rotatable frame, a plurality of pressing units carried by said frame, means for rotating said frame in a step-by-step manner and means for locking said frame against rotation between said steps; said rotating means being 105 110 115 120 125 130

capable of being rendered inoperative at the will of the operator in order to permit the pressing units to be completely filled one at a time when the machine is started in operation.

In witness whereof, I hereunto set my hand this third day of May, 1926.

LESLIE A. HOLMAN.
